HYDRAULIC DUPLICATING MECHANISM
AND DIRECTIONAL CONTROLManuel Turchan, Dearborn, and Curtis Walker,
Detroit, Mich.

Application July 26, 1943, Serial No. 496,240

41 Claims. (Cl. 90—13.5)

This invention relates to a machine tool duplicating attachment, and more particularly to an automatically controlled mechanism governing relative circumambulatory movement of a cutter and a work table supported work-piece.

Still more particularly the invention relates to means governing relative longitudinal and cross feeding movement of a cutter and a work-piece whereby a pattern or templet of irregular shape may be completely reproduced by a continuous relative 360 degree traverse of the cutter with respect to the work-piece; or by a plurality of continuous 360 degree traverses.

It will be understood that the templet and work-piece are supported in spaced relation upon a suitable work table, as for instance the work table of the machine tool to which the present attachment is adapted to be secured, with a tracer provisioned relative to said templet and adapted for circumambulatory 360 degree movement with respect thereto.

Movements of the tracer spindle reacting to the sides of the templet are adapted to control alternately the longitudinal and cross feed of said work table and cutter, there being hydraulic motors or cylinders secured to said table at right angles, with their hydraulic fluid pressure connections from a suitable hydraulic unit being governed by said tracer.

In the present invention however, only one feed cylinder, either longitudinal or cross feed, will at any moment be under tracer control. While one cylinder is thus under tracer control the other is under constant fluid control from the hydraulic unit, through a directional control valve, and entirely independent of the tracer.

It being desirable at different points in a circumambulatory traverse around a work piece and templet pattern to change tracer control from one feed to the other, a suitable directional control valve is employed the detail of which is set out below and in our co-pending application Serial Number 449,354, filed July 1, 1942.

However said directional control valve receives one of two sources of tracer controlled fluid to be directed to one end or the other of either of the two feed cylinders. Said directional control valve also receives a constant fluid source from a hydraulic unit to be directed to one end or the other of the feed cylinder not under tracer control. By quarter turns of the directional control valve in one direction or the other, as explained hereafter in detail, there can be a complete relative circumambulatory traverse of 360 degrees, or a plurality of such traverses of the work-piece

relative to the cutter, at the same time as similar relative movements are effected between the templet and tracer.

It is the object of the present invention to provide an automatic tracer operated control for the directional control valve whereby rotary adjustments of said valve may be made automatically so that no matter what the shape is of the pattern sought to be reproduced, a complete 360 degree traverse of its surfaces may be made without manual adjustment of the directional control valve.

It is a further object of the present invention to provide a hydraulically actuated piston operably connected to the directional control valve for effecting quarter turns successively in one direction, together with another hydraulically actuated piston operably connected to said directional control valve for effecting quarter turns successively thereof in the opposite direction.

It is the further object hereof to provide a tracer controlled valve for directing fluid impulses to one of said pistons or the other to thereby automatically control the rotary quadrantal adjustment of said directional control valve.

It is the still further object herein to provide a constant fluid source from the hydraulic unit to said pistons for returning the same respectively to their inoperative positions after having effected a quarter turn of the directional control valve, whereby upon the next fluid impulse, the pistons will be ready, one or the other to effect an additional quarter turn of the directional control valve in one direction or the other.

It is the still further object of this invention to provide a tracer having a spindle controlled valve adapted for directing fluid from the hydraulic unit to one end or the other of either the longitudinal or cross feed cylinder depending upon longitudinal positions of said valve above or below a certain predetermined neutral position.

It is the further object herein to provision exhaust fluid governing means within said spindle actuated valve whereby exhaust fluid from both feed cylinders can be directed therethrough before being returned to the hydraulic unit, it being understood that such control of the exhaust fluids from the feed cylinders also effects control of the feeding of the work table, slowing down the same in proportion to the amount of spindle deflection.

Thus while a reasonably small deflection may result in partial slowing down of the feed movement, an extreme or abnormal deflection may

cause actual stoppage of both feeds, preventing damage to the work piece, to the cutter or to the tracer under certain conditions.

It is the further object of this invention to provide an automatic control for the directional control valve characterized by a plurality of piston operated lever mechanisms for effecting one quarter rotational adjustments of said directional control valve.

It is the further object herein that said lever mechanisms be actuated electrically under the control of the tracer mechanism, as by a plurality of solenoids, for accomplishing the desired translational movement of said lever mechanisms.

It is the further object herein to provide a third dimensional vertical control in combination with the two directional horizontal control, with a suitable secondary tracer adaptable for engagement with a model, thereby providing a completely automatic three directional controlled duplicating attachment.

These and other objects will be seen in the following specification and claims showing the various elements and their various operative combinations, as illustrated in the accompanying drawings of which—

Fig. 1 is a front elevational view of a milling machine showing the duplicating attachment.

Fig. 2 is a partially sectional complete diagrammatic view illustrating the hydraulic connections and operative relations of the control mechanisms.

Fig. 3 is a diagrammatic view of a regularly shaped pattern with the numbered arrows indicating positions of the tracer spindle and the corresponding adjusted positions of the directional control valve rotary member.

Fig. 4 is a diagrammatic view of an irregularly shaped pattern with the numbered arrows indicating progressive positions of the tracer spindle and directional control valve rotary member.

Fig. 20 is a fragmentary partially sectioned view showing a slightly different arrangement of the two directional control tracer and the automatic control mechanism for the directional control valve coupled thereto.

The above drawings illustrate merely preferable embodiments of the invention herein, it being distinctly understood that other embodi-

ments are contemplated within the scope of the invention hereinafter set out, described and claimed.

Referring to the drawings, Fig. 1 shows a standard milling machine with supporting base 11, longitudinally adjustable work table 12, and the transversely adjustable cross feed work table supporting slide 13.

Slide 13 is suitably supported upon base 11, there being a cross feed cylinder 14 secured to said slide adapted for reciprocable movement with respect to a stationary piston 14' and piston rod 14'' therein anchored to said base. Similarly work piece and templet supporting table 12 is longitudinally reciprocable by means of the reciprocable cylinder 15 secured thereto and adapted for movement with respect to the stationary piston 16 and piston rod 17, the latter being suitably anchored to the cross feed slide 13.

A cutter 18 is rotatably journaled above table 12 with provision made for vertical adjustment as desired by means of the vertically adjustable slide 19 which suitably supports cutter 18, said slide itself being adjustably provisioned upon the upright portion 20 forming a part of the base 11 of the milling machine.

A movable cylinder 2 is suitably secured to slide 19 adapted for reciprocable vertical movement with respect to the stationary piston 3 and piston rod 4 secured to the column 20 at point 5.

Tracer 21 is carried by column 11 being universally mounted for adjustment relative to cutter 18, there being a supporting arm 22 secured to column 11, to which is secured vertical tracer adjustment means 23, longitudinal adjustment means 24 and the cross adjustment means 25.

The secondary tracer 6 governing vertical feed movements of cylinder 2 is carried by the bracket 7 joined to the vertically adjustable slide 19 and movable therewith, there being a vertically adjustable means 8 interposed therebetween for positioning said tracer relative to model 9 on work table 12.

Spindle 26 having a pattern engaging tracer tip 27 is longitudinally disposed within tracer housing 21 as shown in Fig. 2, carrying at its upper end the cylinder control valve piston 28. Said piston having annular openings 29, 30, 31, 32 and 33 is adapted for slight reciprocable movement within tracer sleeve 10 which has corresponding annular fluid conducting openings 34, 35 and 36.

A piston rod 37 is carried at the upper end of piston 28 being slidably disposed through nut 38 and the spring tension adjusting nut 39 for the valve piston engaging spring 40. A bracket member 41 disposed across the top of tracer sleeve 10 and suitably secured thereto carries at its other end the control housing 42 which has provisioned therein the annular openings 43 and 44.

A control piston 45 having fluid conducting annular openings 46, 47 and 48 is slidably disposed within housing 42, and adapted for longitudinal adjustment therein by means of the upwardly extending piston rod 49 suitably secured thereto. Piston rod 49 is actuated reciprocably by lever 50 pivoted at 51 to the fulcrum 52, its respective ends carrying studs 53 and 54 which are respectively nested within the discs or members 55 and 56 carried by piston rods 49 and 37.

Thus upon movement of spindle 26 upwardly on engaging an irregularity or change in the contour of the templet movement may be also imparted downwardly to the control piston 45. It will be understood however that it is desirable

that the relative movement of piston 28 and piston 45 be unequal; and this can be accomplished by regulating the operative ends of lever 50.

On the other hand downward movement of spindle 26 under action of spring 40 will cause an upward movement of the control piston 45. It will be understood that such downward movement of spindle 26 may represent a substantial change in direction of the peripheral surface of the templet.

Referring to Fig. 2 the hydraulic unit is generally indicated at 57 for supplying fluid under pressure by means of a suitable pump, not shown, out through conduit 58 to the tracer sleeve opening 30, through conduit 59 to the control housing opening 47, through conduit 60 to port 60' of the directional control valve housing 61, and through conduit 62 to the ends of the directional control valve operating cylinders 63 and 64.

In neutral position of valve piston 28 with the tracer tip 27 out of engagement with the templet, it will be noted that by action of the spring 40 said piston will be slightly below the position shown in Fig. 2. Fluid directed from the hydraulic unit 57 through conduit 58 and sleeve opening 30 will then enter valve opening 34 and be directed out through conduit 67 to the directional control valve 61 at port 67'.

In the manner fully set out hereunder said fluid is directed, in one position of the directional control valve rotor member 11 to one end for instance, of longitudinal feed cylinder 15 through conduit 66 causing tracer controlled longitudinal feeding of work table 12 to the right.

With tracer controlled fluid directed through conduit 66, exhaust fluid returns to the directional control valve through conduit 68, and to the tracer through conduit 65 to enter valve opening 35. It will be noted that in the previously depressed position of piston 28 said exhaust would be free to enter sleeve opening 31 for direction through conduit 69, governor inlet 32, opening 36, and governor outlet 33, to be returned to the hydraulic unit 57 through conduit 70.

As soon, however, as the tracer tip 27 contacts the pattern slightly, spindle 26 will be projected upwardly to its central inoperative position so that further longitudinal feeding is stopped, inasmuch as fluid from opening 30 can no longer enter valve opening 34. As cross feeding at the moment, hereafter described in detail is constant, in accordance with a change in the contour of the templet 27', spindle 27 will be projected upwardly so that fluid at opening 30 will be conducted into valve opening 35 and thence through conduit 65 to the directional control valve at port 65'.

With the directional control valve in its same adjusted position, said tracer controlled fluid is then conducted to the opposite end of the longitudinal feed cylinder 15 through conduit 68 causing an immediate reversal of longitudinal feeding to the left.

In this same position of the rotary member 11 of the directional control valve exhaust fluid from cylinder 15 is conducted back to the direction control valve through conduit 66, whence said exhaust is directed back to the tracer through conduit 67, where in the elevated position of piston 28, it is free to enter the exhaust opening 29. Said exhaust fluid is then directed to exhaust conduit 69 into the exhaust governor inlet 32 where it communicates with sleeve opening 36, valve opening 33, and conduit 70 back to the hydraulic unit 57.

As set out in detail in the above referred to co-pending application, Serial No. 449,354 relating to the directional control valve, and also in our co-pending application, Serial No. 366,082, relating to two directional feed control, with tracer controlled fluid directed to the longitudinal feed cylinder 15 through conduits 66 or 68, the cross feed cylinder 14 is under constant feeding. Fluid under pressure is supplied from the hydraulic unit 57 directly to the directional control valve through conduit 60 where in the same position of the rotary member therein constant fluid will be directed to one end of the cross feed cylinder 14, for instance through conduit 71. With the piston stationary, cylinder 14 moves outwardly towards the observer, while the exhaust fluid on the other side of the piston is returned through conduit 72 back to the directional control valve.

From the directional control valve the exhaust fluid returns through conduit 73 to the tracer controlled exhaust governor inlet 32, passing through the sleeve opening 36, and governor outlet 33, back to the hydraulic unit 57 through conduit 70.

It will be understood that constant fluid under pressure, independent of the tracer, may be directed from the directional control valve through conduit 72 which would cause constant cross feeding outwardly in the opposite direction, away from the observer. In this event the exhaust fluid returns through conduit 71 to the directional control valve, and then through conduit 73 to governor openings 32, 36, 33, and conduit 70 back to the hydraulic unit.

In reproducing a work-piece from a templet where a 360 degree circumambulatory traverse is contemplated, or a plurality of such traverses accompanied by an indexed relative vertical feeding is intended, or an automatic tracer controlled vertical feeding, it is desirable that the tracer tip pressure against the edge of the templet be substantially tangent to the surface thereof at its point of contact. As shown in Fig. 3 for instance by the numbered arrows 1, 2, 3 and 4 arranged around the diagrammatic indication of the regularly shaped pattern 74, the co-action of the tracer tip shown by said arrows is perpendicular to the point of contact of the tracer and also towards the templet.

As set out in our co-pending applications Serial No. 449,354 and Serial No. 366,082, the number 1 arrow indication represents the position of the rotary member 11 of the directional control valve 61 which will provide tracer control to the cross feed cylinder at the time that the longitudinal feed cylinder is under constant feeding. With the tracer spindle relatively stationary and with the templet 27' upon the work table 12 being fed relative thereto it is desirable that in effect, a circumambulatory traverse of the pattern be obtained, so that in effect the tracer relatively walks completely around the templet.

As the tracer relatively nears one end of the pattern in order to maintain the tracer tip 27 action towards and substantially perpendicular to the pattern or templet it is necessary to effect a quarter turn of the direction control valve rotor 11 in for instance, a clockwise direction, which has the effect of changing tracer control to the longitudinal feed cylinder and changing constant feeding to the cross feed cylinder. This position of the directional control valve is indicated by the arrow indication number 2.

The number 3 arrow indication with tracer control again in a cross feed cylinder is obtained

by a third quarter turn progressively of the directional control valve rotary member. And finally again the number 4 arrow indication representing tracer control in a longitudinal feed cylinder at the end of the pattern is attained by the fourth progressive quarter turn of the directional control valve.

Fig. 5 diagrammatically indicates the four quadrantial positions of the rotary member of the directional control valves numbers 1, 2, 3 and 4, in order to obtain the inward urge of the tracer tip towards and substantially perpendicular to the edge of the templet throughout the relative circumambulatory traverse of the tracer with respect thereto.

It will be seen that when the edge of the templet is substantially regular as shown in Fig. 3, the progressive one quarter turns of the directional control valve are all in the same clockwise direction for obtaining a complete 360 degree circumambulatory traverse of the templet.

Naturally the tracer movement can be reversed in direction, or at least the relative movement by progressive quarter turns of the directional control valve rotor 77 in the opposite or counter-clockwise direction.

From the numbered arrow indications shown in the irregularly shaped templet 75 in Fig. 4, corresponding to the required positioning shown in Fig. 5, for obtaining an inward substantially right angular urge of the tracer tip relative to the templet it is seen that the quarter turns required will not all be in the same direction but will be varying as indicated.

Thus after the first three one quarter turns of the directional control valve in a clockwise direction, referring to Fig. 4, it will be necessary to go from the number 3 position back in a counterclockwise direction one quarter of a turn to again go to the number 2 position. Again the next adjustment of the directional control valve will be another one quarter turn in a counterclockwise direction to obtain the number 1 position again.

Progressively the next adjustment will again be clockwise one quarter turns to positions 1, 2, 3 and 4, then counterclockwise progressively one quarter turns to the number 3 and number 2 positions etc.

Thus it is seen that for an irregular circumambulatory traverse, the directional control valve will not be operated entirely clockwise in quarter turns, but will be intermittently turned clockwise and then counterclockwise, a quarter turn at a time until a complete traverse is obtained.

The hand wheel 76 shown in Figs. 1 and 2 is adapted to accomplish manually the necessary quarter turns of the directional control valve as desired in the manner previously above set out in detail. However as hereafter described, means are provided for obtaining such directional control valve adjustments automatically without the attention of an operator, and entirely independent of the above referred to hand wheel 76.

Referring to Fig. 2 and also Figs. 11 through 16 the directional control valve is indicated at 61 with the four cylinder ports 66', 68', 72' and 71'. Constant pressure fluid from hydraulic unit 57 is directed to the directional control valve at port 60' through conduit 60, to be exhausted through port 73' and conduit 73 back to the tracer as above described.

The directional control valve housing 61 has a tracer controlled fluid source coming in through

conduit 65 at port 65' and returning to the tracer through port 67' and conduit 67. Or on the other hand depending upon the positioning of tracer spindle 28, tracer fluid may come to the directional control valve through conduit 67 and return through conduit 65.

The manually rotatable member 77 shown in detail in various sections in Figs. 11-16 is rotatably journaled within the directional control valve housing 61 for directing constant pressure fluid entering at port 60' out through any of the cylinder ports 66', 68', 72' or 71'. Likewise said rotatable member is adapted to direct tracer controlled fluid coming into the directional control valve at either port 65' or 67' out through one of the cylinder ports 71', or 72', 68' or 66'.

Furthermore said rotor 77 provides exhaust connections for the other two cylinder ports not delivering fluid, either constant pressure or tracer controlled. Constant pressure exhaust fluid is conducted back to the directional control valve exhaust port 73' to be directed back to the tracer governor through conduit 73 as above described in detail.

Further, exhaust fluid from the cylinder under tracer control is returned through said rotatable member to either port 67' or 65' back to the tracer through either conduit 67 or 65 in the manner above described.

Said rotor, shown in Figs. 11-16, has provisioned longitudinally therein the non-communicating passages 160, 161, 162 and 163 all terminating at one end of said rotor in the four radially positioned passages 160', 161', 162' and 163', each of which is adapted for progressive communication, on rotation of member 77 a quarter turn at a time, with each of the ports 65', 60', 73' and 67' respectively shown in Fig. 2. It is understood that said quarter turn adjustments of rotor 77 are accomplished either manually through rotatable hand wheel 76 or automatically by the tracer operated automatic control fully described in detail hereinafter.

A plurality of annular recesses 164, 165, 166, 167 are provisioned within plunger 77 to coincide with the corresponding cylinder ports 66', 68', 72' and 71' as shown in Fig. 2.

Longitudinal opening 160 terminates at outlet 168 within annular opening 164 to establish fluid communication with the corresponding cylinder port 66'. Longitudinal openings 161, 162 and 163 all of varying lengths from opening 160 likewise respectively terminate at outlets 169, 170 and 171 provisioned around rotor 77, to establish fluid communication effectively with the corresponding cylinder ports 68', 72' and 71' in the directional control valve housing 61.

Consequently in turning the rotor 77 a quarter of a turn at a time i. e. ninety degrees in one direction or the other it is possible to establish communication from any one of the ports 65', 60', 73' and 67' in the direction control valve housing to any desired cylinder port 66', 68', 72' or 71' in said housing for providing fluid control to any particular end of either the longitudinal or cross-feed cylinders 15 or 14. And at the same time to also provide communication from the other inlet ports 65', 60', 73' or 67' to each of the other remaining ends of said cylinders.

For example fluid under constant pressure through conduit 60 from hydraulic unit 57 travels via port 60', passage 161', channel 161, outlet 169, cylinder port 68', and conduit 68 to one end of the longitudinal feed cylinder 15. Exhaust 75 from the other end of said cylinder returns via

conduit 66, cylinder 66', passage 168, channel 160, radial passage 160' and port 73' for direction through conduit 73 back to the tracer governor for subsequent exhausting.

At the same time tracer controlled fluid goes from conduit 65 into the directional control valve housing at port 65' and via passages 163', 163, outlet 171 and port 71', and conduit 71 to one end of the cross-feed cylinder 14. The exhaust from the other side thereof goes back via conduit 72, cylinder port 72' and passages 170, 162, 162', port 67' and conduit 67 back to the tracer.

In operation in progressively traversing the cutter 18 relatively around work-piece 18' corresponding to a relative circumambulatory traverse between the tracer 27 and the templet 27' if it is desired to change the constant feed from the longitudinal feed cylinder 15 to the cross-feed cylinder 14, with tracer control changed from the cross feed cylinder to the longitudinal feed cylinder, all that is necessary is to rotate the plunger 77 a quarter of a turn counterclockwise.

Constant feed travels via port 60', channels 163', 163, 171 and port 71' and conduit 71 to one end of the cross feed cylinder 14. While exhaust from the other side of said cylinder flows back to the directional control valve via conduit 72, port 72', and channels 170, 162, 162', and port 73' and through conduit 73 back to the tracer.

At the same time tracer control goes to the longitudinal feed cylinder 15, via port 65' and channels 160', 160, 168, cylinder port 66' and conduit 66, to cylinder 15 and the exhaust on the other side of said cylinder returns via conduit 68, port 68' and channels 169, 161, 161', and port 67' and conduit 67 back to the tracer for exhausting through the governor mechanism above described.

Thus it is seen that a versatile directional control valve is provided for governing longitudinal and cross feeding of the work piece supporting table with respect to a rotatable cutter whereby it is seen that upon adjustment of the directional control valve rotor in quarter turns at a time in one direction or the other that a complete 360 degree relative circumambulatory traverse may be obtained between the cutter 18 and the work-piece 18' corresponding to a similar 360 degree relative circumambulatory traverse of the tracer 27 with respect to the templet 27'.

Constant feeding may be changed from longitudinal feeding in one direction to cross feeding in one direction. By further rotation 90 degrees of rotor 77 constant feed may be again directed to the longitudinal feed cylinder in the opposite direction; and by another quarter turn of the hand wheel constant feed could go to the cross feed cylinder in the opposite direction.

Referring to Figs. 2 and 8 the shaft of the directional control valve rotary member indicated at 77 is adapted for rotation progressively in quarter turns either clockwise or counterclockwise. Generally the hydraulic control cylinders 63 and 64 are adapted for causing rotation of shaft 77. Cylinder 63 has therein a piston 78 and a reciprocable rod 79 the outer end of which is secured by bracket 80 to rack gear 81.

Likewise cylinder 64 has reciprocably provisioned therein piston 82 and rod 83, on the outer end of which is secured the bracket 84 for transmitting longitudinal movement to the rack gear 85.

In Fig. 2 piston 82 is in its inoperative position being so adjusted by virtue of the constant fluid source directed to cylinders 63 and 64 through conduit 62 from the hydraulic unit 57.

As described hereafter there are two idler gears 86 and 87 on shaft 77 one adapted for rotating said shaft clockwise a quarter of a turn at a time and the other for rotating the shaft counter-clockwise one quarter of a turn at a time. These gears each respectively turn the shaft in only one direction, and movement of the gears respectively in the opposite direction is merely an idling motion permitting each of the rack gears to return to its initial inoperative position ready for the hydraulic impulse from the control valve hereafter described which will cause its longitudinal gear operating movement.

Fluid under pressure from hydraulic unit 57 is supplied through conduit 59 to the control housing opening 47 where, depending upon movement of control piston 45, is adapted to be directed outwardly through either piston opening 43 or 44 to conduits 88 or 89 respectively. Conduit 88 directs fluid to the end of control cylinder 63 and conduit 89 directs fluid under pressure from the control housing 42 to control cylinder 64.

Piston 78 of cylinder 63 is shown in Fig. 2 in its operative position at the end of its operative stroke after having translated rack gear 81 which is adapted to operatively engage the idler gear, for instance, gear 86, in the manner now described in detail in connection with Figs. 6 and 7.

The directional control valve fragmentarily indicated at 61 in Fig. 6 with its rotatable shaft member 77, is suitably secured to hand wheel 76 by the nut 90 and member 102, whereby said directional control valve may be manually adjusted to any of the various quadrantal positions previously described.

A cylinder supporting plate 91 is provided secured by studs 92 to the directional control valve housing 61. Control cylinder 63 is carried by plate 91, being secured thereto by screws 93; while control cylinder 64 is secured thereto by screws 93'.

Piston 78 is shown within cylinder 63 secured to the reciprocable rod 79 on the end of which is bolted bracket 80 for reciprocating rack gear 81, the latter being adapted for sliding reciprocable movement within the recessed longitudinal groove 94 formed within cylinder 63.

The corresponding rotatable idler gear 86 is provisioned in mesh with rack gear 81 being rotatably and loosely journaled on the rotatable sleeve 96, the latter being adapted for rotation with the rotatable member 77 forming the rotor for the directional control valve 61.

It will be noted however that said rotatable sleeve is loose upon rotatable shaft 77 but may be locked with respect thereto for movement in unison therewith.

To accomplish this, sleeve 96 is slotted at 97 for receiving the reciprocable piston member 98 having an operating piston rod one end of which 99 projects through the outside of sleeve 96, while its other end 100 is adapted to project within the transverse slot 101 formed within the rotatable member 102 secured to hand wheel 76 and also to rotatable member 77.

A manually operable cantilever handle 103 pivotally mounted at 104 is loosely secured at its operating end at 105 to the outer end 99 of

piston rod 100. By action of coiled spring 106 piston 98 is normally urged inwardly causing the inner end 100 of the piston rod to be nested within opening 101 of member 102.

So positioned, it is seen that rotary movement of sleeve 96 will cause movement in unison therewith of hand wheel 76 and likewise rotary movement of the directional control valve rotary shaft 77, when under automatic operation. However, on manual operation of handle 103 in a clockwise direction, sleeve 96 is disengaged, and hand wheel 76 may be manually operated independently of sleeve 96 and the automatic control.

Thus it is seen that during automatic operation, now described further, hand wheel 76 is adapted to also move corresponding to the rotary movement of sleeve 96.

Rotary member 102 secured to the rotatable shaft 77, is radially slotted at 106' for slidably nesting ratchet member 107, the latter being itself recessed for receiving coiled spring 108 which is adapted to normally urge said ratchet member outwardly with respect to member 102 and within a corresponding notch 109 shown in Fig. 7, formed within the inner surface of the idler gear 86. It will be noted that ratchet 107 projects up through a suitable opening 95 in sleeve 96.

Said ratchet member is angularly inclined at 110 whereby it is seen that movement of idler gear 86 independent of member 102 will be permitted in one direction only i. e. clockwise as it is returned by action of rack gear 81 to its initial position. On the other hand it will be noted upon rotation of idler gear 86 in a counter-clockwise direction upon longitudinal translation of rack gear 81 to the left under action of the automatic control that said rotation of gear 86 will cause a corresponding quarter turn rotation counter-clockwise of the rotatable member 102 and the rotor 77 of the directional control valve 61.

Immediately after this initial fluid impulse from conduit 88 causing a quarter turn counter-clockwise of the directional control valve rotary member, piston 78 will be promptly returned to its initial position to the right by virtue of the constant fluid pressure provided from the hydraulic unit through conduit 62.

Consequently it will be seen that piston member 78 is again ready for another fluid impulse from the hydraulic control valve causing longitudinal movement of rack gear 81 to the left and another quarter turn counter-clockwise movement of the rotor member 77. It is seen that after each progressive quarter turn idler gear 86 is returned clockwise to its initial position which is readily permitted forcing the ratchet member 107 inwardly against the action of coiled spring 108.

In a similar manner it will be seen that rotatable member 102 is also radially slotted at 111 for slidably receiving the ratchet member 112 which is also slotted for receiving the coiled spring 113 interposed therebetween and the rotatable member 102. It will be noted that ratchet member 112 as shown in Fig. 9 is provided with an angular surface 114 oppositely inclined from the angular surface 110 of ratchet member 107, whereby said ratchet is adapted for operative engagement with idler gear 87 which is loosely journaled also around the rotatable sleeve 96, said gear also having a ratchet recess 115 for receiving operatively the upper end of ratchet 112.

Consequently it will be seen that longitudinal movement of piston 82 in cylinder 64 to the left causing a corresponding longitudinal movement of rack gear 82 thus causes a clockwise movement of idler gear 87 which by the position of ratchet member 112 is adapted to cause a clockwise movement of rotatable member 102 and the rotor 77 secured thereto.

Similarly after the initial stroke of rack gear 85 to the left, fluid under pressure from the hydraulic unit 57 through conduit 62 immediately returns piston 82 to its initial position, to the right at the same time returning rack gear 85 and idler gear 87 which is free to rotate in a counter-clockwise direction without effecting movement of the rotary member 102. Thus it is seen that idler gear 87 is again ready for its next hydraulic impulse from the hydraulic control housing 52 through conduit 89 whereby another quarter movement in a clockwise direction of rotor 77 would be obtained.

As previously explained the control housing 42 provides fluid supply conduits 88 and 89 respectively to the ends of the cylinders 63 and 64. Thus, depending upon the positioning of piston 45 within control housing 42, fluid will be directed through either conduit 88 or 89, or alternately through either conduit or by successive fluid impulses through either of said conduits. This will result in obtaining automatic movements of the directional control valve rotor member 77 continuously in a counter-clockwise direction as indicated by the successive numerals 1, 2, 3 and 4 in Fig. 3, utilizing merely the control cylinder 64.

Or on the other hand in the case of an irregularly shaped pattern as shown in Fig. 4 the directional control valve rotor member will be actuated successively clockwise and then counter-clockwise depending upon the curvature of the pattern as shown in Fig. 4.

From the above description it is seen on longitudinal translation of rack gear 81 as in Fig. 7, causing counter-clockwise one quarter rotation of the idler gear 86 and consequent counter-clockwise one quarter rotation of the directional control valve rotor 77, that immediately after this movement, by action of constant low pressure fluid from the hydraulic unit 57 through conduit 62, rack gear 81 is returned to its initial position to the right ready for the next fluid impulse through conduit 88 from the tracer operated automatic hydraulic control valve.

The return of rack gear 81 to the right causes a clockwise free idler movement of gear 86 with the ratchet member 107 forced inwardly by action of the inner surface of said idler upon the inclined surface 110 of said ratchet.

In a similar manner translation to the left of rack gear 85 by action of fluid through conduit 89 causes clockwise movement of idler gear 87 and likewise clockwise movement of the rotor 77 of directional control valve 61. Similarly after its stroke to the left, fluid pressure is relieved in line 89 by piston 45 returning to a neutral position, and constant low pressure fluid through conduit 62 causes the rack gear 85 to return to its initial position at the right, with the ratchet member 112 forced inwardly by action of the inner surface of said idler upon the inclined surface 114 of said ratchet. This in turn causes a free counter-clockwise movement of idler gear 87 independent of rotatable members 102 and 77 returning said idler to its initial inoperative position.

Operation

In operation, referring to Figs. 3 and 4, it is noted that templets 74 and 75 respectively have certain critical points of change in curvature direction, as for instance adjacent points 117, 118, 119 and 120 in Fig. 3. It is seen with the tracer tip 27 engaging templet 74, with constant longitudinal feeding to the left and tracer control in the cross feed, that when the tracer reaches the point 117, the change in direction becomes more sudden, permitting a more pronounced dropping away of the tracer tip 27, spindle 26 and also the tracer controlled valve 28.

This more pronounced downward movement is translated through piston rod 37, lever 50, piston rod 49, to the control piston 45 within control housing 42. Naturally this downward movement of tracer spindle 26 causes a corresponding upward movement of control piston 45 whereby fluid communication is intermittently established between the fluid line 59, port 47 and the control piston port 44. Thus fluid under pressure is directed out through conduit 89 causing piston 82 to traverse the length of its cylinder 64.

As above described this traverse causes a longitudinal operative translation of rack gear 85 causing rotation of idler gear 87 one quarter of a turn. In the manner above described a quarter or 90 degree rotation of the directional control valve rotor 77 is imparted, which has the effect of changing tracer control from the cross feed cylinder 14 to the longitudinal work table feed cylinder 15. At the same time, as above described, constant feeding is changed from the longitudinal feed cylinder 15 to the cross feed cylinder 14.

This reversal of tracer control again permits the tracer spindle 26 to assume a normal position, or at least is subject only to the normal amount of tracer deflection for normal tracer controlled feeding. Consequently, control piston 45 is returned to its initial neutral position cutting off the flow of fluid through conduit 89 to cylinder 64.

By action of the constant low pressure fluid from the hydraulic unit 57 through conduit 62, piston 82 is again returned to its normal inoperative position ready for the next fluid impulse from the control valve 45.

Referring to Fig. 3 intermittent fluid impulses will be received progressively at approximately the marked points 117, 118, 119 and 120, each fluid impulse causing a quarter revolution of the directional control valve rotor 77. Said rotor therefore makes one complete 360 degree movement, while the tracer and templet have also made a corresponding relative 360 degree traverse.

It will be noted here that the normal tracer deflection has no effect upon the control valve piston 45, this being accomplished by regulating the length of the arms of lever 50 so that the average normal deflection of the tracer spindle 26 will effect no fluid control through control valve housing 42.

It will be seen that for the traverse of the pattern shown in Fig. 3, that only cylinder 64 need be employed for accomplishing the progressive clockwise quarter turns of the directional control valve rotor, inasmuch as tracer tip 27 on reaching each of the critical points 117, 118, 119 and 120 tends to drop to a greater extent than is otherwise encountered where the tracer covers the normal traverse, as for instance between points 120 and 117.

However referring to Fig. 4 it will be seen that the tracer tip if taken to be represented by the

circled numerals, as it traverses relatively in a clockwise direction around the templet 75, will be adapted to relatively extreme downward movements as in Fig. 3, but also will encounter certain changes in direction which will cause a relatively extreme upward deflection as for instance at points 121 and 122.

As the tracer tip reaches substantially the location of the point 121 an upward deflection occurs which will be greater than the normal upward deflection encountered as for instance the deflection encountered by the tracer when traversing templet 74, Fig. 3, from point 120 to point 123.

This upward deflection is similarly translated through piston rod 37, pivoted lever 50 and piston rod 49, to cause a downward control movement of piston 45. This will result in establishing fluid communication from conduit 59 to port 47, and port 43, permitting fluid under pressure to be directed out through conduit 88 to the end of the control cylinder 63. Fluid so directed will cause a longitudinal translation of piston 18, and likewise of rack gear 81 causing a counter-clockwise quarter turn of the idler gear 86, which as previously explained causes a corresponding quarter turn of the rotor member 77 of the directional control valve 61. It will be noted that the quarter turn rotation caused by fluid traveling through conduit 88 is the opposite in direction from the quarter turn rotation caused by fluid traveling through conduit 89.

Consequently the directional control valve rotor 77 is changed from its number 3 position as indicated in Fig. 4 to its number 2 position. And again on the tracer encountering point 122 there will be another upward deflection which, in the manner above described, will cause another quarter rotation of the directional control valve rotor 40 to its number 1 position.

As the tracer approaches the point 124 there will again be another pronounced downward movement of the tracer spindle 26 which will result in a quarter clockwise turn of the directional control valve rotor under action of fluid to cylinder 64.

It will be noted after the initial impulse of fluid from the control valve to either cylinder 63 or 64, that this supply of fluid is cut off with the result that low pressure fluid through conduit 62 causes return of the pistons to their normal positions. From the illustration of Fig. 2 it will be seen that fluid in the upper part of cylinder 63 will be returned to the control valve housing through conduit 88, ports 43 and 46, whence it will be directed through conduit 125 back to the hydraulic unit 57. Similarly fluid returning through conduit 89 will be directed through piston recess 44, sleeve recess 48 and conduit 125 back to said hydraulic unit.

As above described in detail the directional control valve rotor 77 is adaptable to successive one quarter or ninety degree rotational adjustments in either a clockwise or counter-clockwise direction. In connection with Figs. 2, 6 and 7 this result is accomplished through hydraulic cylinders 63 and 64; however it is contemplated that the same result be accomplished electrically utilizing the same tracer arrangement.

A plurality of micro-switches are employed. Contact with one switch by a relatively accentuated tracer movement downwardly causes operation thereof for actuating a lever means through 75 a suitable solenoid causing one quarter turns

of the directional control valve in a clockwise direction.

On the other hand another switch is employed operable on accentuated upward movement of the tracer spindle. This latter switch is also adapted to cause the operation of another solenoid and lever for rotatably actuating the directional control valve rotor, one quarter of a turn at a time in the opposite or counterclockwise direction.

Referring to Fig. 10 a contactor 126 is shown adaptable to vertical upward or downward movement being suitably mounted on the piston member 28 shown in Fig. 2.

On the other hand contactor 126 could be operable through the auxiliary piston rod 49 connected thereto in the manner illustrated with respect to the connection of rod 49 to the piston 45 in Fig. 2. In any event, and for the sake of illustration, let it be assumed that an accentuated upward movement of tracer spindle 26 will cause an upward movement of contactor 126. On the other hand an accentuated downward movement of spindle 26 will cause the corresponding downward movement of contactor 126.

A micro-switch is indicated at 127 electrically operable upon upward movement of contactor 126, said switch controlling relay box 128 grounded at 129, through wires 130, whereby a current impulse from the source of current 131 is directed through wire 132 to solenoid coil 133 grounded at 134.

The longitudinally movable member 135 within coil 133 is adapted upon energization thereof to cause a translation to the left of the support 136 to which is pivotally joined at 137 lever 138. Said lever pivotally mounted at 139 is adapted for pivotal movement around axis 139 whereby the outer end 140 of lever 138 may be employed as an intermittent actuating means to the right for obtaining through a suitable ratchet mechanism described hereinafter, one-quarter turns in one direction of directional control valve rotor 77.

In a like manner a second micro-switch 141 is operable upon downward movement of contactor 126, to actuate relay box 142 grounded at 143 by means of the electrical wires 144. In turn, relay box 142 permits a current impulse from the power source 145 to travel through wire 146 to solenoid coil 147, the latter being grounded also at 134.

On energization of coil 147 the longitudinally movable member 148 causes a translation to the left of lever support 149 to which is pivoted lever 150 at point 151. Said lever pivotally mounted at 152 thereby provides a translatory movement to the right of its outer end 153 to which may be attached suitable ratchet means for rotatably actuating with one quarter turns at a time the directional control valve rotor 77, but in the direction opposite to the direction of rotation imparted by solenoid 133.

The electrical tracer actuated mechanism above described in conjunction with Fig. 10 is adapted for effecting quarter turns of the directional control valve rotor 77 in the manner illustrated in Figs. 17 through 19.

While Fig. 17 illustrates a hydraulic method of actuating levers 138 and 150, as described hereafter, yet the same arrangement is perfectly adaptable to the corresponding solenoid actuated levers 138 and 150 described in conjunction with Fig. 10.

With the reciprocable supports 136 and 149 shown both in Figs. 10 and 17, it is contemplated that their reciprocable movements be effected

either electrically in the manner illustrated in conjunction with Fig. 10 or hydraulically as illustrated in Fig. 17.

It will be noted that rotational movement of rotor 77 of the directional control valve 61 was accomplished hydraulically as shown in Figs. 2, 6, 7 and 8 by means of the rack gears 84 and 85, and the idler gears 86 and 87. However Fig. 17 illustrates a hydraulic method for accomplishing this result employing levers 138 and 150 instead of gears.

Referring to Fig. 17 the lever 138 pivoted to housing 154 at 139 is joined to the reciprocable support 136 at 137 as shown also in Fig. 10. Upon downward movement of support 136, it is seen that upward movement is imparted to the outer end 140 of lever 138.

A cantilever 155 joins lever 138 at 140 whereby downward movement of support 136 causes an upward translation of cantilever 155. Said cantilever has a ball shaped actuating means 156 at one end thereof with its other end joined at 157 to the coiled spring 158 anchored to housing 154 at point 159.

Rotatable shaft 77 of directional control valve 61 has keyed thereon the two ratchet cam members 160 and 161 arranged in spaced relation, cam 161 being shown in Fig. 17 as having the four quadrantly disposed notches 162 intermittently and progressively engageable by the ball means 156 on the end of cantilever 155 hereafter described. On the other hand the ball actuating means 156 of cantilever 155 is adapted to engage similar notched recesses 163 in the cam member 160.

A suitable guide pin 163 is carried by housing 154 adaptable for guidingly engaging the edge of cantilever 155. In operation, on downward movement of support 136, with spring 158 maintaining cantilever 155 against pin 163, an upward movement is imparted to the ball means 156 causing the same to operatively engage the cam 160 within one of its notches 162 which correspond to notches 163 of cam 161.

A 90 degree rotational movement is thus imparted to rotor 77 after which, support 136 is returned to its initial position, as where the solenoid coil is de-energized as described in connection with Fig. 10. On support 136 returning upwardly to its inoperative position the end 140 of lever 138 is dropped downwardly causing the ball means 156 to disengage cam member 160.

From the above description, an accentuated movement upwardly of the tracer spindle caused when the tracer tip engages the point 121 in Fig. 4, will effect through solenoid 133, a translation to the left of support 136. This corresponds to a downward movement of the support 136 shown in Fig. 17. This movement thus causes thru lever 138 a ninety degree rotational movement counter-clockwise of rotor 77 of the directional control valve, causing said rotor to turn from its number 3 position of Fig. 4 to its number 2 position.

Again on the tracer reaching point 122 in Fig. 4 another accentuated upward movement is effected in the tracer spindle, which again causes another ninety degree rotation of directional control valve rotor 77 through operation of cantilever 155. Now as the tracer reaches point 124 of templet 75 in Fig. 4, an accentuated downward movement of the tracer spindle results, causing actuation of contactor 126 against the micro-switch 141.

This in turn causes operation of solenoid 147 causing movement to the left of support 149, and pivotal movement of lever 150 counter-clockwise. Referring to Fig. 17 this movement corresponds to the translation to the right of support 149 and the lever 150 joined thereto at 151. Said lever pivoted to housing 154 at 152 is thus given a translatory movement of its outer end 153 to the left causing a corresponding movement of cantilever 164.

Said cantilever pivotally joined to lever 150 at 153, has a ball actuating means 165 at one end, with its other end at 166 being joined to spring 167 anchored to housing 154 at 159. A corresponding cam member 161 identical with cam 166 is also keyed to shaft 77 of directional control valve 61, having corresponding notches 162 arranged similarly to notches 168 of cam 160. Thus upon translation to the right of support 149, a corresponding translation to the left is effected of cantilever 164 with its ball means 165 on its end operatively actuating cam 161 within one of its notches 162.

A suitable guide pin 169 is also employed secured to housing 154 providing guide means for the return of cantilever 164 at the time that solenoid 147 is de-energized. Thus, as above described, when the tracer spindle arrives approximately at point 124 of templet 75 in Fig. 4, the accentuated downward movement of the spindle causes a 90 degree rotation clockwise of rotor 77 returning the same to its number 2 position shown.

In traversing templet 74 Fig. 3 it is seen that there will be successive accentuated downward movements of the tracer spindle at approximately points 117, 118, 119 and 120, all resulting in successive, but intermittent clockwise ninety degree adjustments of rotor 77 of the directional control valve to the respective numbered positions 4, 1, 2 and 3 shown in Fig. 3.

Again referring to Figs. 17 through 19 specifically it is seen that the ninety degree adjustments of the directional valve rotor 77 may be effected hydraulically. Hydraulic cylinders 170 and 171 are shown at right angles secured exterior of the housing member 154 within which are provisioned levers 138 and 150 for rotatively actuating rotor 77 either clockwise or counter-clockwise as described in detail fully relative to the operation of the electrical actuated means illustrated in Fig. 10.

Reciprocable pistons 172 and 173 and rods 174 and 175 respectively are disposed within cylinders 170 and 171 for actuating the movable lever supports 136 and 149 secured by nuts 176 and 177. High pressure fluid ports 178 and 179 are provided for fluid communication from the automatic tracer operated control valve 42 shown in Figs. 2 and 20 to the respective control cylinders 170 and 171.

As described above in connection with Fig. 2 and more particularly in Fig. 20 depending upon accentuated tracer control movements, fluid supplied to the control valve 42 through conduit 59 from hydraulic unit 57 travels out through either conduits 88 or 89 to the control cylinders 170 or 171 respectively.

Such control fluid enters cylinder 170 at port 178, or cylinder 171 through port 179, for obtaining the initial translation of the pistons 172 or 173. As also above explained, with the control piston 45 returned to its neutral position, constant low pressure fluid is directed from the hydraulic unit 57 to the opposite ends of cylinders

170 and 171 through conduit 62, causing either piston last operative to return to its neutral position. For this purpose low pressure ports 180 and 181 are provided respectively.

5 The exhaust fluid from cylinders 170 and 171 returning through either conduit 88 or 89 is returned back to the hydraulic unit through conduit 125 in the manner fully explained in connection with Fig. 2.

10 Referring again to Figs. 17 through 19 the shaft 77 of directional control valve 61 indicated fragmentarily in Fig. 19, is manually operable through hand wheel 76. It is noted that the housing 154 for the levers 138 and 150, cantilevers 155 and 164, and cylinders 170 and 171, is 15 suitably secured to the directional control valve housing 61 by the bolts 182 as in Fig. 19.

15 Fig. 19 shows the two notched cams 160 and 161 secured to rotatable shaft 77 with cantilever 155 shown in engagement with cam 160. From these illustrations it is seen that cantilevers 155 and 164 after their operative engagement with cams 160 and 161 respectively, are disengaged therefrom so that it appears clear that either 20 cantilever is operable independently of the other.

25 It will be noted that the illustration of Fig. 20 corresponds closely to the illustration of Fig. 2 with the exception that the tracer housing 10 and control housing 42 are shown in greater detail. From the detail in Fig. 20 it is seen that spindle 26 is independent of the control piston 28 within the tracer sleeve 10.

30 Spindle 26 has provisioned at its upper end the Y shaped cone race 182, within which is nested the ball bearing retainer 183 for friction minimizing engagement with the corresponding annularly arranged bottom portion 184 of the tracer control valve 28.

35 By virtue of the angular relation specified 40 lateral pressure upon tracer tip 27 from the templet causes upward movement of the valve piston 28. Piston rods 37 and 49 however are interconnected differently than shown in Fig. 2. A fulcrum supporting member 185 is provisioned 45 upon the connector plate 41 providing a base for the fulcrum 186 which is adjustably threaded upon the lever 187.

50 Said lever has ball ends 188 and 189 adjustably secured by the connection members 190 and 191 threadably secured respectively upon the upper 55 end of piston rods 37 and 49, whereby it is seen that manual adjustments may be made between said rods for regulating the corresponding movements thereof.

55 By varying the positioning of fulcrum 186 on lever 187 the response of the control valve 45 may be adjusted relative to the movement of the tracer controlled piston 28. This adjustment is arranged so that the nominal deflections 60 of the tracer spindle will not appreciably effect the control valve 45. While on the other hand the accentuated upward and downward movement of the spindle, on encountering certain critical changes of direction in the edge of the templet, will cause operation of the control piston 45 for regulating the rotary adjustments of 65 directional control valve 61, all as fully described in detail herein above.

60 Referring to Figs. 1 and 2 a secondary tracer 6 is shown carried by brackets 7, and the vertically adjustable slide 19 governing vertical movement of cutter 18. It is contemplated that in addition to the complete 360 degrees circumambulatory traverse effected between the tracer 65 27 and templet 27', and cutter 18 and work piece

18', there will also be automatic tracer controlled relative vertical feed movements of the cutter 18 relative to said work piece.

This is accomplished by the secondary tracer 6 wherein tracer spindle 192 is adapted to cooperatively engage model 9 also supported upon work table 12. Said model is so formed as to correspond in profile to the vertical configuration of the pattern sought to be reproduced in the work piece.

The tracer construction is the same as that shown in Fig. 20 but with the governor openings 32, 33 and 36 omitted. As shown diagrammatically in Fig. 2 tracer 6 is supplied fluid under pressure from the hydraulic unit 67 through conduit 194, with an exhaust conduit 195 shown for returning exhaust fluid from the vertical feed control cylinder 2.

Depending upon the vertical positioning of the spindle actuated valve within tracer 6, fluid is thus supplied under pressure to cylinder 2 through either conduit 196 or 197 to one side or the other of piston 3 therein. Thus by operation of fluid through either conduit 196 or 197 vertical movements will be effected of the cylinder 2 relative to the stationary piston rod 4 secured to the milling machine slide support 20 at point 5.

Cylinder 2 being secured to the cutter carrying slide 19, it is seen that automatic vertical adjustments of the cutter may be effected at the same time as the relative 360 degree circumambulatory traverse is effected between cutter 18 and work piece 18'.

It will be understood that the references herein to a pattern engaged by the tracer and a templet engaged by the tracer are synonymous in the present application wherein templet and pattern are intended to refer to the illustrations of Figs. 3 and 4.

Having described our invention, reference should now be had to the claims which follow for determining the scope thereof.

We claim:

1. The combination with a cutter and work support relatively movable transversely in two directions; of a tracer engageable with a templet for controlling relative movement in one direction of said work support; a constant fluid pressure source controlling relative movement in a second direction; a safety exhaust mechanism within said tracer for limiting relative movement in said second direction; a directional control valve for regulating said relative transverse movements, and adapted to transfer tracer control from one transverse movement to the other, and change the constant fluid pressure source from one transverse movement to the other, and at the same time switching said safety mechanism from one transverse movement to the other, and means joining said tracer with said directional control valve for causing automatic adjustments of the latter.

2. The combination with a rotatable cutter, of a work support movable relatively in two directions at right angles, a plurality of cylinders with movable pistons secured to said support for reciprocably moving the same for longitudinal and cross-feeding; of a tracer adapted to relatively engage a templet for regulating fluid under pressure to said cylinders, controlling longitudinal feed, a constant fluid pressure source for cross feeding, a safety valve in said tracer for governing the cross-feed; a directional control valve for alternately changing tracer con-

trol from longitudinal to cross-feed, and said constant feed from cross-feed to longitudinal feed, and at the same time changing the safety control from cross-feed to longitudinal feed, and tracer operative means engageable with said directional control valve for causing automatic adjustments thereof.

3. In a hydraulic profiling and contouring duplicating mechanism, a cutter; a work support 10 relatively and reciprocably movable in two directions by virtue of a plurality of movable pistons in hydraulic cylinders for transverse longitudinal and cross feeds of said support; a templet engaging tracer for controlling one of the transverse feeds, a constant fluid pressure source for operating the other transverse feed, a safety valve within and operated by said tracer for limiting said other transverse feed; a directional control valve for changing tracer control from one transverse feed to the other, and said constant fluid pressure source from one transverse feed to the other, and tracer controlled means operatively engaging said directional control valve for automatically adjusting the same.

4. In a hydraulic profiling and contouring duplicating mechanism, a cutter; a work support relatively and reciprocably movable in two directions by virtue of a plurality of movable pistons in hydraulic cylinders for transverse longitudinal and cross feeds thereof; a templet engaging tracer for controlling one of the transverse feeds; a constant fluid pressure source joined to the other transverse feed, a safety valve operable within said tracer for controlling said other transverse feed; a directional control valve for changing tracer control from one transverse feed to the other, changing the constant fluid source from one transverse feed to the other; and for changing safety valve control from one transverse feed to the other, said directional control valve being rotatable into positions for alternately regulating reciprocation of said transverse feeds, and tracer operative means engageable with said directional control valve for causing automatic rotational adjustments thereof.

5. In a hydraulic profiling and contouring duplicating mechanism having a cutter and a work support relatively movable in two directions at right angles, and having a plurality of 50 cylinders with reciprocable pistons secured to said support for actuating the same; a tracer adapted to engage a templet, a plurality of valves within said tracer and actuated thereby, for controlling fluid to one of said cylinders, and exhaust from the other, a hydraulic unit for producing fluid under pressure to said tracer, and a constant fluid source exterior of said tracer, a directional control valve for switching tracer control from one transverse feed movement to the other, and switching the constant pressure source from one transverse feed to the other, conduits from said hydraulic unit to said tracer, to said directional control valve, and from the latter to said cylinders, and tracer operative means engageable with said directional control valve for causing automatic adjustments thereof.

6. In a hydraulic profiling and contouring duplicating mechanism having a cutter and a plurality of cylinders for transverse longitudinal and cross feeding of a work table relative to said cutter, and having a tracer with a control valve and a governor valve for controlling the hydraulic connections to said cylinders; a directional control valve comprising a housing having 70 cylinder ports adaptable for fluid connection to

75

the opposite ends of the cylinders governing transverse feeding, and inlet and return ports adapted for connection to both ends of said control valve, to a governor exhaust valve in said tracer, and to a constant fluid pressure source; and a rotatable member within said valve, having a plurality of non-communicating longitudinally disposed channels, communicating with each of said cylinder ports, and adapted for alternate communication with each of said inlet and return ports, whereby turning of said rotatable member is adapted to regulate the reciprocation of said transverse feeds and also intermittently reverse tracer control from one transverse feed cylinder to the other, changing the constant fluid source from one transverse feed to the other, at the same time shifting governor valve control from one transverse feed cylinder to the other, and operative means interconnecting said tracer control valve and said directional control valve for effecting automatic adjustments of the rotatable member therein.

7. In a hydraulic profiling and contouring duplicating mechanism having a cutter and a plurality of cylinders for transverse longitudinal and cross-feeding of a work table relative to said cutter, and having a tracer with control valve and exhaust governor valve for regulating the hydraulic connections to said cylinders; a directional control valve comprising a housing having a plurality of cylinder ports for fluid connection to the opposite ends of the transverse feed cylinders, and inlet and return ports adapted for connecting with said control valve in said tracer, with said governor, and with a fluid pressure source; a rotatable member therein having a plurality of non-communicating channels adapted for continuous fluid communication separately at the ends thereof with each of said cylinder ports, the other ends of said channels having radial openings in said rotatable member adapted for progressive alternate communication with each of said inlet and return ports, and operative means interconnecting said tracer control valve and said directional control valve rotatable member for effecting progressive automatic adjustments thereof.

8. In a hydraulic profiling and contouring duplicating mechanism having a cutter and a plurality of cylinders for transverse longitudinal and cross feeding of a work table relative to said cutter, and having a tracer with control valve and exhaust governor valve for regulating the hydraulic connections to said cylinders; a directional control valve comprising a housing having a plurality of inlet and return ports and cylinder ports, a rotatable member journaled therein with a plurality of spaced annular openings coinciding separately with each cylinder port, there being a plurality of non-communicating channels within said member, separately joining on their ends each of said annular openings, the other ends thereof having independent radial channels separately joining each of said inlet and return ports, each of said cylinder ports being adapted, upon movement of said rotatable member, to progressively and alternately communicate with each of said inlet and return ports, and operative means interconnecting said control valve and said directional control valve rotatable member for effecting automatic ninety degree adjustments thereof.

9. In a hydraulic profiling and contouring duplicating mechanism having a cutter and a plurality of cylinders for transverse longitudinal and cross feeding of a work table relative to said cut-

ter, and having a tracer with a control valve for regulating the hydraulic connections to said cylinders; a directional control valve comprising a housing having a plurality of cylinder ports and a plurality of radially spaced inlet and return ports, a manually rotatable member journaled therein having a plurality of longitudinally spaced annular recesses separately coinciding with each cylinder port, there being a plurality of non-communicating channels of varied lengths within said member, separately joining at their ends each of said annular recesses, the other ends of said channels having independent radial channels for separately communicating with each of said inlet and return ports, each of said latter channels being adapted upon rotation of said member to progressively communicate separately with each of said radial inlet and return ports, and a plurality of operative means for causing successive and alternate ninety degree movements of said rotatable member in opposite directions.

10. The combination, a plurality of fluid cylinders for causing relative longitudinal and cross feeding movement between a cutter and a work support, a directional control valve joined by conduits to said cylinders for regulating movement thereof, a rotary member within said directional control valve adapted for directing tracer controlled fluid to one cylinder and constant pressure fluid to the other cylinder, alternately and to opposite ends thereof, a tracer engageable with a pattern for regulating tracer controlled fluid to said directional control valve, fluid operative means engageable with said directional control valve rotatable member for turning the same in opposite directions, a secondary control valve communicating with said fluid operative means, and means interconnecting said tracer and said secondary control valve.

11. The combination, a plurality of fluid cylinders for causing relative longitudinal and cross-feeding movement between a cutter and a work support, a directional control valve joined by conduits to said cylinders for regulating movement thereof, a rotary member within said directional control valve adapted for directing tracer controlled fluid to one cylinder and constant pressure fluid to the other cylinder, alternately and to opposite ends thereof, a tracer engageable with a pattern for regulating tracer controlled fluid to said directional control valve, oppositely disposed fluid cylinders engageable with said rotatable member for turning the same in opposite directions, a secondary control valve communicating by conduits with said latter fluid cylinders, and operative means interconnecting said tracer and said secondary control valve.

12. The combination, a plurality of fluid cylinders for causing relative longitudinal and cross feeding movement between a cutter and a work support, a directional control valve joined by conduits to said cylinders for regulating movement thereof, a rotary member within said directional control valve adapted for directing tracer controlled fluid to one cylinder and constant pressure fluid to the other cylinder, alternately and to opposite ends thereof, a tracer engageable with a pattern for regulating tracer controlled fluid to said directional control valve, oppositely disposed fluid cylinders having reciprocable pistons therein engageable with said rotatable member for turning the same in opposite directions, a secondary fluid control valve communicating by conduits with the ends of said latter fluid cylinders for causing successive and intermittent ninety de-

gree rotation of said rotatable member in opposite directions, and operative means interconnecting said tracer and said secondary control valve.

13. The combination, a plurality of fluid cylinders for causing relative longitudinal and cross feeding movement between a cutter and a work support, a directional control valve joined by conduits to said cylinders for regulating movement thereof, a rotary member within said directional control valve adapted for directing tracer controlled fluid to one cylinder and constant pressure fluid to the other cylinder, alternately and to opposite ends thereof, a tracer engageable with a pattern for regulating tracer controlled fluid to said directional control valve, oppositely disposed fluid cylinders having reciprocable pistons therein engageable with said rotatable member for turning the same in opposite directions, a secondary fluid control valve communicating by conduits with the ends of said latter fluid cylinders for causing successive and intermittent ninety degree rotation of said rotatable member in opposite directions, operative means interconnecting said tracer and said secondary control valve, and conduits communicating with the opposite ends of said latter cylinders providing a constant fluid pressure source for normally maintaining the pistons therein in inoperative position.

14. The combination, a plurality of fluid cylinders for causing relative longitudinal and cross feeding movement between a cutter and a work support, a directional control valve joined by conduits to said cylinders for regulating movement thereof, a rotary member within said directional control valve adapted for directing tracer controlled fluid to one cylinder and constant pressure fluid to the other cylinder, alternately and to opposite ends thereof, a tracer engageable with a pattern for regulating tracer controlled fluid to said directional control valve, operative means on said rotary member, oppositely disposed fluid cylinders having reciprocable pistons therein engageable with said operative means for turning the same in opposite directions, a secondary fluid control valve communicating by conduits with the ends of said latter fluid cylinders for causing intermittent translation of the pistons joining said operative means for providing ninety degree rotation of said rotatable member in either direction, operative means interconnecting said tracer and said secondary control valve, and conduits communicating with the opposite ends of said latter cylinders providing a constant fluid pressure source for normally maintaining the pistons therein in inoperative position.

15. The combination, a directional control valve housing joined by conduits to opposite ends of longitudinal and cross feed cylinders, a rotary member within said directional control valve adapted for directing tracer controlled fluid to one cylinder and constant pressure fluid to the other cylinder, alternately and to opposite ends thereof, oppositely disposed fluid cylinders having reciprocable pistons therein, and operative means carried by said pistons adapted to independently engage said rotary member for causing intermittent successive one quarter turns thereof in the same direction and in opposite directions.

16. The combination, a directional control valve housing joined by conduits to opposite ends of longitudinal and cross feed cylinders, a rotary member within said directional control valve adapted for directing tracer controlled fluid to

one cylinder and constant pressure fluid to the other cylinder, alternately and to opposite ends thereof, oppositely disposed fluid cylinders having reciprocable pistons therein, operative means carried by said pistons adapted to independently engage said rotary member for causing intermittent successive one quarter turns thereof in the same direction and in opposite directions, and a secondary tracer controlled valve joined by conduits to the ends of said latter cylinders for causing translation of either of said piston carried operative means.

17. The combination, a directional control valve housing joined by conduits to opposite ends of longitudinal and cross feed cylinders, a rotary member within said directional control valve adapted for directing tracer controlled fluid to one cylinder and constant pressure fluid to the other cylinder, alternately and to opposite ends thereof, oppositely disposed fluid cylinders having reciprocable pistons therein, operative means carried by said pistons adapted to independently engage said rotary member for causing intermittent successive one quarter turns thereof in the same direction and in opposite directions, a secondary tracer controlled valve joined by conduits to the ends of said latter cylinders for causing translation of either of said piston carried operative means, and a constant fluid pressure source joined to the opposite ends of said latter cylinders for causing return of said operative means independent of said rotary member.

18. The combination, a directional control valve housing joined by conduits to opposite ends of longitudinal and cross feed cylinders, a rotary member within said directional control valve adapted for directing tracer controlled fluid to one cylinder and constant pressure fluid to the other cylinder, alternately and to opposite ends thereof, oppositely disposed fluid cylinders having reciprocable pistons therein, and operative means carried by said pistons adapted to independently engage said rotary member for causing upon translation thereof in one direction, intermittent successive one-quarter turns thereof in the same direction and in the opposite direction, and a constant fluid pressure source joined to the opposite ends of said latter cylinders for causing return of said operative means independently of said rotatable member.

19. The combination, a directional control valve housing joined by conduits to opposite ends of longitudinal and cross feed cylinders, a rotary member within said directional control valve adapted for directing tracer controlled fluid to one cylinder and constant pressure fluid to the other cylinder, alternately and to opposite ends thereof, oppositely disposed fluid cylinders having reciprocable pistons therein, rack gears carried by said pistons, idler gears carried by said rotatable member and in mesh with said rack gears respectively, and means interposed between said idler gears and said rotary member whereby upon movement of said rack gears alternately in one direction, rotational movement of said rotary member will be effected, while movement of said rack gears in the other direction, rotational movement of said rotary member will not be effected.

20. The combination, a directional control valve housing joined by conduits to opposite ends of longitudinal and cross feed cylinders, a rotary member within said directional control valve adapted for directing tracer controlled fluid to one cylinder and constant pressure fluid to the

other cylinder, alternately and to opposite ends thereof, oppositely disposed fluid cylinders having reciprocable pistons therein, rack gears carried by said pistons, idler gears carried by said rotatable member and in mesh with said rack gears respectively, and means interposed between said idler gears and said rotary member whereby upon movement of said rack gears alternately in one direction, rotational movement of said rotary member will be effected successively in one-quarter turns in one direction and in opposite directions, and a constant fluid pressure source joined to the opposite ends of said latter cylinders for causing return of said rack gears to their initial positions independent of said rotary member.

21. The combination, a directional control valve housing joined to opposite ends of longitudinal and cross feed cylinders, a rotary member therein adapted for directing tracer controlled fluid to one cylinder and constant pressure fluid to the other cylinder, alternately and to opposite ends thereof, oppositely arranged lever means adapted to operatively engage said rotary member, adaptable upon translation thereof for causing progressive one-quarter turns of said rotary member in the same direction and in opposite directions, electrically operable means adapted for causing separate translation of said lever means, and a selective tracer controlled switch means for causing operation of either of said electrically operable means.

22. The combination, a directional control valve housing joined to opposite ends of longitudinal and cross feed cylinders, a rotary member therein adapted for directing tracer controlled fluid to one cylinder and constant pressure fluid to the other cylinder, alternately and to opposite ends thereof, separately operable ratchet means engageable with said rotary member, lever means joining said ratchet means adaptable upon translation thereof for causing progressive one-quarter turns of said rotary member in the same direction and in opposite directions, electrically operable solenoids to which said lever means are joined for causing intermittent translation thereof, electrically operable relay means joining each of said solenoids, micro-switch means joining each of said relay means, and a tracer actuated contactor for independently engaging either of said switch means for causing rotary movements of said direction control valve rotary member.

23. The combination with a cutter and work support relatively movable transversely in two directions at right angles, a feed cylinder connected to each support to move the same a tracer engageable with a pattern for controlling one of said cylinders for relative movement in one direction; a constant fluid pressure source controlling the other cylinder for relative movement in a second direction; a directional control valve regulating said relative movements, and adapted to reverse tracer control from one cylinder to the other, and change the constant fluid pressure source from one cylinder to the other, and means joining said tracer with said directional control valve for causing automatic adjustments thereof, whereby a continuous 360 degree relative traverse is effected between tracer and pattern, and cutter and work support.

24. The combination with a stationary rotatable cutter, of a work support movable relatively in two directions at right angles, and a plurality of cylinders with movable pistons secured to said

support for reciprocably moving the same for longitudinal and cross-feeding; of a tracer adapted to engage a pattern for regulating fluid under pressure for controlling the longitudinal feed cylinder; a constant fluid pressure source for controlling the cross feed cylinder; a directional control valve for alternately changing tracer control from longitudinal to cross feed, and said constant feed from cross feed cylinder to longitudinal feed cylinder, and means joining said tracer with said directional control valve for causing automatic rotational adjustments thereof, whereby a continuous 360 degree relative traverse is effected between tracer and pattern, and cutter and work support.

25. In a hydraulic profiling and contouring duplicating mechanism, a cutter; a work support relatively movable in two directions by virtue of a plurality of movable pistons in hydraulic cylinders for transverse longitudinal and cross feeds of said support; a pattern engaging tracer for controlling one of the feed cylinders; a constant fluid pressure source for operating the other feed cylinder; a directional control valve for changing tracer control from one feed cylinder to the other, and said constant fluid pressure source from one feed cylinder to the other, and means joining said tracer with said directional control valve for causing automatic adjustments thereof whereby a continuous 360 degree relative traverse is effected between tracer and pattern, and cutter and work support.

26. In a hydraulic profiling and contouring duplicating mechanism, a cutter; a work support relatively and reciprocably movable in two directions by virtue of a plurality of movable pistons in hydraulic cylinders for traverse longitudinal and cross feeds of said support; a pattern engaging tracer for controlling one of the feed cylinders; a constant fluid pressure source joined to the other feed cylinder; a directional control valve for changing tracer control from one feed cylinder to the other, and changing the constant fluid source from one feed cylinder to the other, said directional control valve being movable into position for alternately regulating reciprocation of said transverse feed cylinders, and means joining said tracer with said directional control valve for causing automatic adjustments thereof whereby a continuous 360 degree relative traverse is effected between tracer and pattern, and cutter and work piece.

27. In a hydraulic profiling and contouring duplicating mechanism having a cutter and a work support relatively movable in two directions at right angles with respect to each other, and having a plurality of cylinders with reciprocable pistons secured to said support for actuating the same; a tracer adapted to engage a pattern, a valve therein for controlling fluid selectively to either of the two cylinders, a second valve for controlling the exhaust fluid from the cylinder not under tracer control, a hydraulic unit for providing fluid under pressure to the feed cylinder controlling valve in said tracer, and also a constant fluid source exterior to said tracer for the feed cylinder not under tracer control, a directional control valve mechanism for switching tracer control from one transverse feed cylinder to the other, and switching the constant pressure source from one transverse feed to the other respectively, suitable conduits from said hydraulic unit to said tracer to said directional control valve and said cylinders, and means joining said tracer with said directional

control valve for causing automatic adjustments thereof.

28. In a hydraulic profiling and contouring duplicating mechanism having a cutter and a work support relatively movable in two directions at right angles with respect to each other, and having a plurality of cylinders with reciprocable pistons secured to said support for actuating the same; a tracer adapted to engage a pattern, a valve therein for controlling fluid selectively to either of the two cylinders, a hydraulic unit for providing fluid under pressure to the feed cylinder controlling valve in said tracer, and also a constant fluid source exterior to said tracer for the feed cylinder not under tracer control, a directional control valve mechanism for switching tracer control from one transverse feed cylinder to the other, and switching the constant pressure source from one transverse feed to the other respectively, suitable conduits from said hydraulic unit to said tracer, to said directional control valve and said cylinders, and means joining said tracer with said directional control valve for causing automatic adjustments thereof.

29. The combination with a cutter and work support relatively movable transversely in two directions by a plurality of cylinders; of a tracer with control valve engageable with a pattern for controlling relative transverse movement in one direction; a constant fluid pressure source controlling relative movement in a second transverse direction, a directional control valve comprising a housing having spaced cylinder ports adaptable for connection to opposite ends of the transverse feed cylinders, and inlet and return ports adapted for connection to both ends of said control valve, and to a constant fluid pressure source, and a rotatable member within said directional control valve having a plurality of non-communicating longitudinally disposed channels, communicating with each of said cylinder ports, and adapted for alternate communication with each of said inlet and return ports, whereby turning of said rotatable member is adapted to regulate the reciprocation of said transverse feeds and also intermittently reverse tracer control from one transverse feed cylinder to the other, changing the constant fluid source from one transverse feed to the other, and operative means interconnecting said control valve and said directional control valve for causing automatic adjustments of its rotatable member.

30. The combination with a rotatable cutter, of a work support movable relatively in two directions at right angles, and a plurality of cylinders with movable pistons secured to said support for reciprocably moving the same for longitudinal and cross feeding; of a tracer adapted to engage a pattern for regulating fluid under pressure controlling longitudinal feed; a constant fluid pressure source for cross feeding; a directional control valve for alternately changing tracer control from longitudinal to cross feed, and said constant feed from cross feed to longitudinal feed, said directional control valve comprising a housing having a plurality of cylinder ports and a plurality of radially spaced inlet and return ports, a manually rotatable member journaled therein having a plurality of longitudinally spaced annular recesses separately coinciding with each cylinder port, there being a plurality of non-communicating channels of varied lengths within said member, separately joining at their ends each of said annular openings, the other ends of said channels having independent

radial outlets for separately joining each of said radial inlet and return ports, each of said channels being adapted upon rotation of said member to progressively communicate separately with each of said radial inlet and return ports, and means joining said tracer with said directional control valve rotatable member for causing automatic adjustments thereof.

31. The combination with a cutter and work support relatively movable transversely in two directions; of a tracer engageable with a pattern for controlling relative movement in one direction of said work support; a constant fluid pressure source controlling relative movement in a second direction; a safety exhaust mechanism within said tracer for limiting relative movement in said second direction; a directional control valve for regulating said relative transverse movements, and adapted to reverse tracer control from one transverse movement to the other, and change the constant fluid pressure source from one transverse movement to the other, and at the same time reversing said safety mechanism from one transverse movement to the other, means joining said tracer with said directional control valve for causing automatic adjustment of the latter, and a secondary tracer operably engageable with a model on said support for regulating relative movement of said cutter and work piece in a third direction.

32. The combination, a plurality of fluid cylinders for causing relative longitudinal and cross feeding movement between a cutter and a work support, a directional control valve joined by conduits to said cylinders for regulating movement thereof, a rotary member within said directional control valve adapted for directing tracer controlled fluid to one cylinder and constant pressure fluid to the other cylinder, alternately and to opposite ends thereof, a tracer engageable with a pattern for regulating tracer controlled fluid to said directional control valve, fluid operative means engageable with said directional control valve rotatable member for turning the same in opposite directions, a secondary control valve communicating with said fluid operative means, means interconnecting said tracer and said secondary control valve, a third cylinder for effecting relative vertical movement of said cutter and work support, and a secondary tracer operable engageable with a model on said support for regulating said vertical movement.

33. The combination, a directional control valve housing joined to opposite ends of longitudinal and cross feed cylinders, a rotary member therein adapted for directing tracer controlled fluid to one cylinder and constant pressure fluid to the other cylinder, alternately and to opposite ends thereof, oppositely arranged lever means adapted to operatively engage said rotary member, adaptable upon translation thereof for causing progressive one-quarter turns of said rotary member in the same direction and in opposite directions, hydraulically operable means adapted for causing separate translation of said lever means, and means joining said tracer with said hydraulic means for causing operation of either of said hydraulically operable means.

34. The combination, a directional control valve housing joined to opposite ends of longitudinal and cross feed cylinders, a rotary member therein adapted for directing tracer controlled fluid to one cylinder and constant pres-

sure fluid to the other cylinder, alternately and to opposite ends thereof, separately operable ratchet means engageable with said rotary member, lever means joined to said ratchet means adapted upon translation thereof for causing progressive one-quarter turns of said rotary member in the same direction and in opposite directions, hydraulically operable cylinders with movable pistons therein joined to said levers for causing separate translation thereof, and tracer controlled means for causing operation of either of said latter cylinders.

35. The combination, a directional control valve housing joined to opposite ends of longitudinal and cross feed cylinders, a rotary member therein adapted for directing tracer controlled fluid to one cylinder and constant pressure fluid to the other cylinder, alternately and to opposite ends thereof, notched cam members on said rotary member, oppositely arranged lever means adapted to operatively and separately engage said cam members, adaptable upon translation of said lever means for causing progressive one-quarter turns of said rotary member in the same direction and in opposite directions, electrically operable means adapted for causing separate translation of said lever means, and a selective tracer controlled switch means for causing operation of either of said electrically operable means.

36. The combination, a directional control valve housing joined to opposite ends of longitudinal and cross feed cylinders, a rotary member therein adapted for directing tracer controlled fluid to one cylinder and constant pressure fluid to the other cylinder, alternately and to opposite ends thereof, notched cam members on said rotary member, oppositely arranged lever means adapted to operatively engage said rotary member, adaptable upon translation thereof for causing progressive one-quarter turns of said rotary member in the same direction and in opposite directions, hydraulically operable means adapted for causing separate translation of said lever means, and means joining said tracer with said hydraulic means for causing operation of either thereof.

37. The combination, a directional control valve housing joined to opposite ends of longitudinal and cross feed cylinders, a rotary member therein adapted for directing tracer controlled fluid to one cylinder and constant pressure fluid to the other cylinder, alternately and to opposite ends thereof, notched cam members on said rotary member, pivotal lever means, cantilever means pivotally carried thereby and adapted to separately engage at their ends each of said cam members, adaptable upon translation thereof for causing progressive one-quarter turns of said rotary member in the same direction and in opposite directions, electrically operable means adapted for causing separate translation of said lever means, and a selective tracer controlled switch means for causing operation of either of said electrically operable means.

38. The combination, a directional control valve housing joined to opposite ends of longitudinal and cross feed cylinders, a rotary member therein adapted for directing tracer con-

trolled fluid to one cylinder and constant pressure fluid to the other cylinder, alternately and to opposite ends thereof, notched cam members on said rotary member, pivotal lever means, 5 cantilever means pivotally carried thereby and adapted to separately engage at their ends each of said cam members, adaptable upon translation thereof for causing progressive one-quarter turns of said rotary member in the same direction and in opposite directions, hydraulically operable means adapted for causing separate translation and pivotal movement of said lever means, and tracer controlled means joining said hydraulically operable means for causing operation of either thereof.

39. The combination with a rotatable cutter and work support relatively movable with respect to each other transversely in two directions at right angles; of a tracer relatively immovable with respect to said cutter and having movable means adapted to react to the contour of a templet sought to be duplicated by said cutter, for controlling relative movement in one direction; a constant fluid pressure source 20 controlling relative movement in a second direction, a directional control valve for regulating said transverse movements, and adapted to transfer tracer control from one transverse movement to the other, and change the constant fluid pressure source from one transverse 25 movement to the other, and means interconnecting said movable means and said directional control valve for causing automatic adjustments of the latter, whereby a continuous 360 degree 30 relative traverse is effected between tracer and pattern, and cutter and work-piece.

40. The combination, a directional control valve housing joined to opposite ends of longitudinal and cross feed cylinders, a rotary member 40 therein adapted for directing tracer controlled fluid to one cylinder and constant pressure fluid to the other cylinder, alternately and to opposite ends thereof, and tracer actuated electrically operable means operably engageable 45 with said rotary member for causing progressive one-quarter turns of said rotary member in the same direction and in opposite directions.

41. The combination with a cutter and work support relatively movable transversely in two directions at right angles, of a tracer engageable with a pattern for controlling relative movement in one direction; a constant fluid pressure source controlling relative movement in a second direction; a directional control valve regulating said relative transverse movements, and adapted to transfer tracer control from one transverse movement to the other, and change the constant fluid pressure source from one transverse movement to the other, means joining 50 said tracer with said directional control valve for causing automatic adjustments thereof, whereby a continuous 360 degree relative traverse is effected between tracer and pattern, and cutter and work support, and a second tracer 55 operably engageable with a model on said support for regulating relative movement of said cutter and work piece in a third direction.
